UNITED STATES PATENT OFFICE.

GEORGE R. SCHOENTHALER, OF CHICAGO, ILLINOIS.

SPACER FOR REINFORCING-BARS.

1,324,359.

Specification of Letters Patent.

Patented Dec. 9, 1919.

Application filed December 11, 1916. Serial No. 136,202.

To all whom it may concern:

Be it known that I, GEORGE R. SCHOENTHALER, a citizen of the United States, residing at the city of Chicago, county of Cook, and State of Illinois, have invented a certain new and useful Improvement in Spacers for Reinforcing-Bars, of which the following is a full, clear, and exact description, such as will enable others skilled in the art to which it appertains to make and use the same, reference being had to the accompanying drawings, forming part of this specification.

This invention relates to certain improvements in spacers for supporting reinforcing rods in predetermined definite positions in the building of concrete structures. It relates particularly to the type of such devices which are characterized by a construction whereby the reinforcing bars are supported not only at a definite predetermined distance from the form, but also at predetermined distances from one another.

It is the object of the present invention to provide a spacer which may be manufactured and used at a minimum cost, and which is possessed of maximum strength and stability. It is likewise my object to provide a device of this sort having a construction such as will avoid the formation of air pockets in the concrete.

Other and further objects will be obvious or pointed out hereinafter.

In the accompanying drawings, I have illustrated two forms in which my invention may be embodied.

Figure 1 being a side elevation of the first form showing a reinforcing bar as retained in place;

Fig. 2, an end elevation of the same;

Fig. 3, an end elevation of the second form; and

Fig. 4 a side elevation of said second form.

By reference to these drawings, particularly Figs. 1 and 2, it will be observed that my device is formed from an integral strip of sheet metal 1 which is slotted transversely at proper intervals partially across its width to form foot members 2. The integrity of the device when thus slotted is maintained by the unslotted continuous bar-engaging portion 4. The leg portions 2 are bent or deflected out of the normal plane of the strip, some to one side thereof, and some to the other, so as to provide a suit-

able supporting base which will maintain the strip upright edgewise. At intervals in the bar-engaging portion 4 may be formed perforations 5 adapted for the passage of tie wires 6.

The use of the device is obvious, it being placed upon the formwork with the lower extremities of the leg portions in contact therewith, and the bars being laid upon the bar-engaging portion 4 and secured to the spacer by the tie wires 6. The apertures 5 for the passage of the tie wires are not essential to the device, as the tie wires may be passed under the bar-engaging portion between the adjacent offset leg portions. In this fashion, the bars are maintained at the proper elevation above the form, and they are also retained in the proper relative spacial relationship. This device forms a very stable spacer, by virtue of the fact that the stresses to which it is subjected are received by the edge of the strip and transmitted transversely of the strip in which direction, of course, the device is most capable of receiving them. While the lateral deflection of the leg portions 2 is sufficient to provide a sufficiently wide base for the support of the device, it should not be to the extent of requiring the metal to carry the weight of the supported bars simply by the thickness of the metal on the line of bend. Also the degree of deflection of the leg portions 2 should be such as to present an edge of the metal for contact with the supporting form structure so that, when the intended load is placed upon the spacer, the edges of the leg members 2 will bite into the supporting form structure to an extent sufficient to prevent the leg portions spreading under the imposed load.

In this fashion, the stresses will be carried by the metal across the entire width of the strip, and by virtue of the fact that all of the leg portions form supporting struts, the load will be distributed throughout the length of the device. Consequently, the device is effective in preventing the downward displacement of the reinforcing structure under the weight of the workman or material upon it, and the movement and pressure of the concrete when it is poured. Furthermore, the device avoids the formation of air holes or voids in the concrete, as it has no arched-over portions and the plastic material is afforded immediate and intimate access to all sides of it. The low

cost of manufacture is obvious from the construction of the device, as it is possible to form it entirely by one machine operation from a strip of sheet metal, and there is no waste of material whatever.

The form of the invention illustrated in Figs. 3 and 4 has, in addition to the legs 2 and bar-engaging portion 4, a laterally turned marginal flange portion 7 along the upper edge of the bar-engaging portion. This laterally turned flange acts as a stiffener to prevent lateral bending of the device. If desired, portions of this lateral flange may be slotted so that they may be deflected upwardly to form ductile retaining fingers 8 to be employed in securing the bars in position on the device. Consequently, the second form of the invention, in addition to the advantages above described with reference to the first form, contains as an integral part the means for securing the reinforcing bars in position on the spacer.

It is obvious, of course, that the invention may be incorporated in forms differing in various particulars from those illustrated and described, and that it is not limited to a device which is intended for coöperation with a plurality of reinforcing bars, but that it may be embodied in a form suitable for use as a clip or support for a single bar. Accordingly, it is my intention that the appended claims be understood to comprehend all forms properly within the scope of the invention.

What I claim is:

1. As a new article of manufacture, a spacer formed of a strip of sheet metal slotted transversely from one of its edges for a portion of its width at longitudinal intervals, the disjoined portions being deflected laterally out of the normal plane of the strip to provide coöoperating supporting struts having their lower margins adapted to contact into a supporting surface, a part of the

unslotted marginal portion of the strip lying 45 in the normal plane and forming a connection for said supporting struts and a support for a bar, a part of said unslotted portion being flanged laterally from the normal plane of the strip to afford a stiffening 50 rib, and a ductile portion operable to retain a bar in position on the marginal portion.

2. As a new article of manufacture, a spacer formed of a strip of sheet metal slotted transversely from one of its edges for a 55 portion of its width at longitudinal intervals, the disjoined portions being deflected laterally out of the normal plane of the strip to provide supporting struts adapted for coöperation at their outer extremities with a 60 supporting surface, a part of the unslotted marginal portion of the strip remaining in the normal plane thereof and forming a connection for said supporting struts, and a part of said unslotted portion being flanged 65 laterally from the normal plane of the strip to form a stiffening member.

3. As a new article of manufacture, a spacer formed of a strip of sheet metal slotted transversely from one of its edges for a 70 portion of its width at longitudinal intervals, the disjoined portions being deflected laterally out of the normal plane of the strip to provide coöoperating supporting legs 75 adapted to contact with a supporting surface at their extremities, a part of the unslotted marginal portion of the strip lying in the normal plane of the strip and forming a connection for said supporting legs, and a part of the unslotted portion being flanged 80 laterally from its original plane and severed by a longitudinal cut to provide a ductile finger bendable about a bar extending transversely of the strip to retain the bar thereon.

In testimony whereof I hereunto affix my 85 signature this 6th day of December, 1916.

GEORGE R. SCHOENTHALER.
